COMBUSTION APPARATUS

Martin De Lin, Holland, Mich., assignor to Holland Furnace Company, Holland, Mich., a corporation of Michigan

Application April 5, 1937, Serial No. 134,983

3 Claims. (Cl. 128—118)

This invention relates to combustion apparatus of the central heating plant type.

The principal object of the present invention is the provision of a self-contained combustion apparatus in which the parts are arranged to provide for the maximum transfer of heat to a fluid to be heated. The invention accordingly resides in the construction and arrangement of the parts of the combustion apparatus herein shown and described.

An illustrative embodiment of the invention is shown in the accompanying drawings, wherein—

Figure 1 is a vertical sectional view of combustion apparatus embodying the present invention, taken on substantially the line 1—1 of Figure 3;

Figure 2 is a vertical sectional view of the apparatus taken on substantially the line 2—2 of Figure 1;

Figure 3 is a horizontal sectional view taken on substantially the line 3—3 of Figure 1;

Figure 4 is a fragmentary elevational view taken on substantially the line 4—4 of Figure 1;

Figure 5 is a fragmentary sectional view taken on substantially the line 5—5 of Figure 1;

Figure 6 is a fragmentary view taken on the line 6—6 of Figure 2;

Figure 7 is a fragmentary horizontal sectional view taken on substantially the line 7—7 of Figure 1; and

Figures 8, 9, 10 and 11 are perspective views of the apparatus in various stages of assembly.

The apparatus illustrated in the accompanying drawings includes several major parts, namely, a supporting frame 10, a heat exchanger 11 mounted upon the supporting frame 10, an inner casing 12 enclosing the heat exchanger, an outer casing 13 enclosing the inner casing, circulating fan units 14, air filters 9, an oil burning unit 15, and an open topped primary combustion chamber 16 disposed within and spaced from the walls of heat exchanger 11. The nozzle of oil burning unit 15 discharges into the chamber 16. The heat exchanger 11, the inner casing 12 and the outer casing 13 are constructed from standard sectional elements whereby the size thereof may be readily varied. Likewise, the filters 9 and fan units 14 are of a character whereby one or more may be used.

The products of combustion formed in the heat exchanger 11 are discharged through exhaust flues 17 and 18 extending through inner casing 12 and outer casing 13. Outer casing 13 is provided with a cold air inlet opening 19 adjacent the top thereof and immediately over the ex-

haust flues 17 and 18. As an alternative to the use of a single air inlet opening 19, the outer casing may be provided with a plurality of smaller openings in its vertical walls as shown at 19a. Communication is provided between the interior of outer casing 13 and the interior of inner casing 12 through means of a pair of openings 20 in the bottom wall of the inner casing 12. The inner casing 12 is provided with an outlet opening 21 in its top wall for the discharge of heated air.

Each of the fan units 14 is operatively associated with one of the openings 20 in the bottom of inner casing 12. They are of the axially intake and radial discharge type whereby the cold air is drawn into the outer casing 13 through inlet opening 19 and then forced through inner casing 12 and out of outlet opening 21. Thus, the air in the outer casing 13 is under a vacuum and the air in the inner casing 12 is under pressure. Consequently, there can be no loss of heat or combustion gases through outer casing 13.

The fans 14 are mounted upon a rotatable shaft 22 which is driven through a driving connection 23 by an electric motor 24. The connection between the discharge outlets of fans 14 and the openings 20 include a flexible tube 14a of canvas or the like (see Fig. 5).

As best shown in Figures 2, 3, 7 and 11, the fan units 14 are housed within a compartment defined by the bottom wall 12a of vertical casing 12, the vertical frame members 8, the vertical walls 6 and 7, and the removable filter units 9. Outer casing 13 is provided with openings in its side walls affording access to the filter units 9 (see Fig. 11). These openings are closed by removable panels. Five filter units are shown, the two on each side of the apparatus being inclined from the vertical to expose a larger surface area to the air traveling vertically downwardly from opening 19. The direction of travel through the apparatus of the air to be heated is shown by the arrows in Figure 2. Thus, it will be seen that all of such air passes through the filters 9.

In order to control the direction of flow of the air passing from outer casing 13 into inner casing 12 through openings 20, there are associated with openings 20 adjustable vanes 30. These vanes distribute the air delivered to the inner casing 12 by the fans 14 in such manner that the air will contact the maximum area of heat exchanger 11 in passing through the inner casing 12.

The heat exchanger 11 is of novel construction.

It includes an expansion chamber 11a surrounding the primary combustion chamber 16 and an economizer chamber 11b adjacent the exhaust flues 17 and 18. The entire heat exchanger 11 is made up of a plurality of sectional compartments 31 and 32 detachably connected to each other. The several sectional compartments 31 form the expansion chamber 11a and the compartments 32 form the economizer chamber 11b.

10 All of the compartments 31 and 32 are of generally elliptical shape in horizontal cross-section, and of substantially rectangular shape in vertical cross-section. They are all formed to provide oppositely disposed side walls of substantially greater extent than the other walls thereof.

15 All of the compartments 31 communicate with each other through aligned restricted openings 33 formed in the sides thereof. These openings are of such size and such character that substantial portions of the opposite side walls of each compartment 31 are directly exposed to the air which is circulated vertically through the inner casing 12 by the fans 14. As best shown in Figures 1 and 3, the openings 33 in compartments 31 provide a straight horizontal passageway for the products of combustion which is of substantially uniform height and width, the height being materially greater than the width.

20 Communication is provided for between the expansion chamber 11a and the economizer chamber 11b by corresponding restricted openings 34 formed in the side wall of adjacent compartments 31 and 32. Communication is provided between the compartments 32 by cooperating restricted openings 35 formed in the adjacent side walls thereof. Communication is provided between the economizer chamber 11b and the exhaust flues 17 and 18 by a pair of restricted openings 36 and 37 in the adjacent side wall of compartment 32.

25 Openings 34 and 35 are the same height as openings 33 but of materially less width. The size and location of all of the openings 34, 35, 36 and 37 are such that a major portion of the side walls in which they are formed are directly exposed to the air circulated through inner casing 12. As best shown in Figure 3, these openings are arranged to form a serpentine passageway through the economizer chamber 11b. The air 30 circulated through inner casing 12 passes between the convolutions of this passageway.

35 Each of the compartments 31 and 32 is provided with four ears 38. The ears on adjacent compartments are formed with aligned openings for the reception of securing rods 40 which together with the clamping nuts 41 at the opposite extremities thereof serve to detachably connect all of the compartments 31 and 32 together in operative relation. Coil spring elements 42 are shown as mounted upon one end of the rods 40 and interposed between the compartment 32 and the adjacent clamping nut 41. Thus, the compartments are connected to each other in a manner to permit the natural expansion and contraction resulting from the changes in temperature produced within the heat exchanger 11.

40 As previously stated, the heat exchanger 11 is mounted upon a supporting frame 10. The supporting frame 10 consists of two spaced apart horizontally extending parallel pipes 10b supported at their opposite ends by vertical pipes 10a. Each pair of vertical pipes 10a are connected to each other by a cross-support 10c. Thus, there is provided a rigid supporting frame for the heat 45 exchanger 11. The rear end of the heat ex-

changer is anchored to the supporting frame by saddles 5, which have an interlocking engagement with the frame and the lower edge of one of the compartments 32 (see Fig. 6). Except for the two saddles 5, the heat exchanger 11 is not connected to the supporting frame in any way, but is merely mounted upon the horizontally extending pipes 10b and held in position by gravity and the surrounding inner jacket 12. Consequently, the compartments 31 and 32 comprising the heat exchanger 11 are free to expand and contract in a horizontal direction longitudinally of the pipes 10b. The ears 38 at the top and bottom of the compartments 31 and 32 prevent horizontal movement of the heat exchanger in a lateral direction 50 relative to the pipes 10b.

55 The opening 33 in the end compartment 31 (right hand side of Figures 1 and 3) is partially closed by a plate 43 provided with a large rectangular opening. A second plate or closure 44 is detachably connected to plate 43 by lugs 44a which hold it in position to close said opening.

60 Closure plate 44 is insulated, as shown, and is provided with an opening through which a conduit extends. Primary combustion chamber 16 is connected to the inner end of the conduit. Burner 15 is connected to the outer end of the conduit. The plate 44, combustion chamber 16, and burner 15, comprise a unitary assembly 65 which can be removed and installed as a unit. Burner 15 is supported by a bracket 45 carried by plate 44. Auxiliary combustion supporting air is admitted to heat exchanger 11 through an opening in plate 44 with which is associated an adjustable closure 46 (see Fig. 4).

65 As clearly shown in Figures 1 and 3, the inner casing 12 and the outer casing 13 are provided with openings in the front end thereof which are closed by the plates 43 and 44. Of course, in this particular zone the inner casing 12 is not spaced from the heat exchanger 11, and the outer casing 13 is not spaced from the inner casing 12. Plates 43 and 44 and burner 15 are enclosed within an auxiliary housing 47.

70 Exhaust flues 17 and 18 are shown as connected to a common chimney flue 48 of uniform cross-sectional area. The upper exhaust flue 18 is provided with a damper 49 whereby to vary the cross-sectional area of that flue to provide for a uniform pressure in the two flues 17 and 18. This is done in order to insure that the products of combustion passing through the two sections of the heat exchanger will be distributed uniformly throughout the vertical extent of the passageway therethrough.

75 The operation of the apparatus herein illustrated and described is as follows:

80 Combustion is initiated in the primary combustion chamber 16 by the oil burner 15. The combustion there initiated expands into the expansion section 11a of heat exchanger 11 and the products of combustion then pass into the economizer section 11b and finally into the chimney flue 48 through the exhaust flues 17 and 18. The expansion section provides a passageway for the products of combustion which is of uniform height and width. The economizer section of the heat exchanger provides a passageway for the products of combustion which is of uniform height and varying width. The use of the two 85 exhaust flues 17 and 18 assures a proper vertical distribution of the products of combustion whereby the heat thereof is distributed to all portions of the sectional compartments 31 and 32.

90 Air is drawn into the outer casing 13 through

the inlet opening 19 by the fans 14. In traveling between the inlet opening 19 and the fans 14 a major portion of the air either passes over the outer surface of the inner casing 12 or over 5 the outer surface of the exhaust flues 17 and 18, absorbing some heat therefrom. The fans 14 force the air from outer casing 13 into inner casing 12 through the openings 20 and out of the inner casing 12 through the outlet opening 21. 10 In traveling through the inner casing 12 the air passes between all of the compartments 31 and 32, and is directly exposed to contact with a substantial portion of the side walls of compartments 31 and a major portion of the side walls 15 of compartments 32. All together, five sides of the heat exchanger are directly exposed to the air passing through inner casing 12. In this manner, a very efficient transfer of heat from the heat exchanger to the air to be heated is effected. 20 In traveling from the outer casing 13 to the inner casing 12, all of the air to be heated passes through the filters 9.

From the foregoing description it will be apparent that the present invention provides a self-contained combustion apparatus, so designed as 25 to obtain the most efficient transfer of heat to the medium to be heated.

While, as previously indicated, the invention resides in the construction and arrangement of 30 the apparatus herein illustrated and described, it will be readily apparent to those skilled in this art that the invention is not limited to such apparatus but may be embodied in various other

forms of apparatus. The scope of the invention is indicated by the appended claims.

I claim:

1. A device of the character described comprising a heat exchanger, an inner casing completely surrounding the heat exchanger having an inlet opening in its bottom wall and an outlet opening in its top wall, an air circulating compartment formed below the inner casing, said circulating compartment being defined in part 5 by a series of filters constituting substantial continuations of a plurality of the side walls of said inner casing, an outer casing surrounding the inner casing and the circulating compartment, said outer casing having an inlet opening adjacent the top thereof, and a circulating unit located in said circulating compartment for drawing air into the outer casing and forcing it through the inner casing, communication being provided between the outer casing and the inner 10 casing solely through the filters forming side walls of the circulating compartment. 15

2. A device of the character defined in claim 1 wherein the filters are arranged at an inclination to the side walls of the inner casing whereby to expose a larger area thereof to the air passing from the outer casing into the circulating compartment. 25

3. A device of the character defined in claim 1 wherein said filters constitute a substantial 30 continuation of at least two of the side walls of the inner casing.

MARTIN DE LIN.
